(57) **CLAIM**

The ornamental design for a cover for a case for battery cells, as shown and described.

DESCRIPTION

In a preferred embodiment, the nature of this product is as a vehicle battery.

FIG. 1 is a left, top, front perspective view of a first embodiment for a cover for a case for battery cells embodying our new design;

FIG. 2 is a front elevational view thereof;

FIG. 3 is a left side elevational view thereof, the right side elevational view being a mirror image of the left side elevational view shown;

FIG. 4 is a rear elevational view thereof;

FIG. 5 is a top plan view thereof;

FIG. 6 is a bottom plan view thereof;

FIG. 7 is a left, top, front perspective view of a second embodiment of a cover for a case for battery cells identical to the first embodiment in front view, side view, rear view and bottom view; and,

FIG. 8 is a top plan view thereof.

The broken line representations to the battery case in FIGS. 1-8 and the bottom panel are for the purpose of illustrating the environment of the cover and form no part of the claimed design. The broken lines on the top surface of FIGS. 7 and 8 illustrate features of the cover that form no part of the second embodiment.
